UNITED STATES PATENT OFFICE

JOSEPH H. BOWMAN, OF PITTSBURGH, PENNSYLVANIA, ASSIGNOR TO AMERICAN STEEL BAND COMPANY, OF PITTSBURGH, PENNSYLVANIA, A CORPORATION OF NEW JERSEY

METHOD OF MAKING HOOPS

Application filed July 29, 1929. Serial No. 382,054.

This invention relates to the manufacture of metal hoops for barrels, kegs, and the like.

An object of the invention is to produce hoops for barrels from sheet metal by an improved process permitting the painting of the hoops while the metal is in sheet form, and also permitting the punching of the hoop blanks while still in the plate. Other objects and advantages of the invention will be apparent to those familiar with the art from the following specification.

Referring to the drawings, Fig. 1 shows a rough cut sheet of steel or other suitable metal as normally delivered from the mill; Fig. 2 shows the sheet of Fig. 1, the dotted lines indicating the trimming of the edges that has taken place to square up the sides of the sheet and reduce it to the exact width desired; Fig. 3 shows the sheet of Fig. 2 punched, squared and sized at both ends; Fig. 4 shows the sheet of Fig. 3 after slitting into a plurality of individual perforated strips or hoop blanks; Fig. 5 shows a hoop after passing through a bending and bead-forming machine ready for riveting; and Fig. 6 is a cross-section on the line VI—VI of Fig. 5, showing the beading applied to one edge of the hoop.

In the manufacture of hoops for nail kegs, barrels, and the like it is desirable for purposes of reinforcement and to give smooth outer edges, to bead one edge of the hoop. It is also desirable to paint the hoops, to reduce corrosion, and for other purposes. Such hoops are made of blanks cut to proper length and width, and perforated at each end so that rivets may be passed through the overlapping perforations when the strip is bent to hoop form.

The method of manufacture employed prior to the present invention has been to make the blanks of what is known as strip steel. This is purchased from the steel mill in strips of the proper width for making a hoop and of a length of several hundred feet. Such strips come in coils. The long strips are unwound, cut to proper lengths for making a single hoop, these are individually perforated at each end, and then beaded.

In recent years there has grown up a de-

mand for the painting of such hoops prior to their use upon barrels. This has presented a very difficult problem, as the painting of the beaded hoops after formation required an expensive dipping or spraying operation, and the paint may either not get into the portion under the bead, or else may collect and stay there in an undesired thickness. On the other hand the painting of the individual strips requires a preliminary unwinding of the strips for passage thereof through a paint bath, or else the individual dipping of the hoop blanks after they have been severed from the strip.

The difficulties encountered in painting such hoops as they have been manufactured prior to the present invention have been such that it has been considered commercially impractical to provide hoops of the kind described in this application in painted form. Furthermore the manufacture of hoops from strip steel, requiring the individual severing and perforation of each hoop length has been comparatively expensive.

The present invention, which comprises the preliminary painting of large sheets, the punching of each end of the sheets simultaneously for all hoop blanks that are to be cut therefrom, and the subsequent beading of the individual strips, has resulted in material economies of manufacture, and in addition has made commercially possible the painting of both sides of the beaded metal hoops at a price that is not prohibitive.

In carrying out the invention metal sheets of proper gage, substantially the length of the hoop blanks desired, and preferably of the width of a multiple of the hoop widths, are purchased from sheet mills.

One distinct advantage in the use of such sheet metal as compared to strips, is that the plates are rolled by a much larger number of mills and are therefore more generally available and obtainable than strips. In addition the plates can be shipped more compactly than the coils of strips, and therefore take a lower freight rate.

Sheet steel as received from the mill is not always exactly dimensioned. The sheets as received, as for example the one marked S

in Fig. 1, are first painted by running them through a paint bath, or in contact with rolls a portion of which dips into the paint bath. By such means one or both sides of the sheets 5 are painted. The sheets are then passed through a drier so that they may be handled for further operations.

The next step is to place the sheet S in a suitable shear, having means for accurately 10 positioning and holding it, and to trim it to reduce the sides 1, 2 to exact parallelism, and the sheet S, to a width that is exactly a multiple of the width of the hoop blanks desired.

The next step is shown in Fig. 3, and consists in simultaneously trimming off an end 15 3 of the sheet S² to exactly square the end as compared to the sides 1 and 2 previously trimmed. At the same time perforations 4, so positioned that they will fall in the middle 20 line of the hoop blanks that are to be made from the plate, are punched. Then the sheet is reversed and the other end 5 is trimmed off, and perforations 6 simultaneously made.

Thereafter the squared, accurately-dimensioned, perforated sheet is run through a slitter which divides the sheet or plate along lines half way between the lines of the perforations 4 and 6, and produces a plurality 25 of hoop blanks 7, the number depending upon the width of the sheet and the width of the 30 individual hoop blanks.

The next step is to take the individual hoop blanks 7, and to run them through a machine which turns over one edge to form a bead 8, 35 as shown in Figs. 5 and 6. This operation also bends the blank 7 up into substantially circular form, as shown in Fig. 5. In this form they are counted and tied into bundles. Generally these bands are shipped to the user 40 who completes the hoop by riveting the two superposed ends together through the perforations 4 and 6.

By the process above described the following advantages are obtained: (a) the hoop 45 blanks may be purchased in sheet form, the sheets being selected of such width and length as to produce a minimum of scrap in subsequently dividing to form the individual blank; (b) the steel in sheet form is more 50 readily obtainable, at lower prices, and may be shipped at lower rates than coiled strip steel; (c) the sheets may be more economically handled in painting operations; (d) the ends of a large number of the hoop blanks 55 may be simultaneously perforated while in the original sheet form by a single machine operation; (e) the squared, sized, painted, perforated sheet may then by a single operation be slit into completed individual hoop 60 blanks ready for the subsequent beading operations.

I claim:

1. The process of making metal hoops comprising accurately sizing sheets of metal of 65 proper gage to a length equal to that of the

hoop blanks desired, and to a width constituting a multiple of the width of the hoop blanks desired, perforating the ends of the sheets at points adapted to lie in the ends of resultant hoop blanks, then slitting the sheets between perforations to proper width for forming the hoop blanks and so as to include perforations in each end thereof, and then individually beading the hoop blanks. 70

2. The process of making metal hoops comprising sizing sheets of metal of proper gage to a length equal to that of the hoop blanks desired, and to a width constituting a multiple of the width of the hoop blanks desired, painting and drying the sheets, perforating the 75 ends of the sheets at points adapted to lie in the ends of resultant hoop blanks, then slitting the sheets to proper width for forming the hoops and so as to include perforations in each end thereof, and then individually beading the hoop blanks. 80

In testimony whereof, I sign my name.
JOSEPH H. BOWMAN.
